UNITED STATES PATENT OFFICE.

ROBERT D. EVANS, OF WILKINSBURG, PENNSYLVANIA, ASSIGNOR TO WESTINGHOUSE ELECTRIC & MANUFACTURING COMPANY, A CORPORATION OF PENNSYLVANIA.

FURNACE-REGULATOR SYSTEM.

Application filed October 30, 1918. Serial No. 260,277.

To all whom it may concern:

Be it known that I, ROBERT D. EVANS, a citizen of the United States, and a resident of Wilkinsburg, in the county of Allegheny and State of Pennsylvania, have invented a new and useful Improvement in Furnace-Regulator Systems, of which the following is a specification.

My invention relates to regulator systems and particularly to regulator systems for governing the operation of electric furnaces.

One object of my invention is to provide a regulator system of the above-indicated character that shall control the operation of a furnace in an efficient manner and be substantially free from hunting action.

Another object of my invention is to provide a regulator system for an electric furnace, having motor-operated electrodes, that shall govern the operation of the motors for raising and for lowering the electrodes in accordance with the current supplied to the furnace and be provided with means for preventing hunting action thereby which is governed in accordance with the operation of the motors.

In electric furnaces, it is very desirable that the movable electrodes be automatically raised and lowered by motors, preferably electric motors, in accordance with the current supplied to the furnace or by the arcs formed by the respective electrodes. Moreover, it is customary to provide electric furnaces of the above character with regulator systems for governing the operation of the motors which control the movements of the electrodes, and the regulator systems are usually provided with anti-hunting devices for stabilizing the operation of the furnaces.

In an electric-furnace-regulator system constructed according to my invention, a motor is provided for raising and lowering each movable electrode of the furnace in accordance with the current flowing through such electrode. Each regulator unit comprises two electromagnets which oppose each other, one of the electromagnets being energized in accordance with the current flowing through the electrode associated with the regulator for governing the operation of two switches which control the op-

eration of the motor for raising and lowering the electrode, and the other one of said electromagnets being operated in accordance with a motor condition, such as the counter-electromotive force of the motor, for preventing hunting action by the regulator. Moreover, the two switches which govern the operation of the motor are provided with auxiliary switch members for completing a dynamic-braking circuit through the motor whenever the regulator is in a normal position.

The single figure of the accompanying drawing is a diagrammatic view of a furnace-regulator system embodying my invention.

Referring to the drawing, an electric furnace 1, embodying two movable electrodes 2 and 3, and a receptacle 4, containing a bath of material 5, is connected to a three-phase supply circuit comprising conductors 6, 7 and 8. The supply conductors 7 and 8 are respectively connected to the electrodes 2 and 3, and the supply conductor 6 is connected to the bath of material 5.

Two motors 9 and 10, respectively comprising armatures 11 and 12, and field windings 13 and 14, are provided for raising and lowering the electrodes 2 and 3 by any suitable means, such, for example, as drums 15 and 16, which are mounted upon the shafts of the armatures 11 and 12, and flexible connecting means 17 and 18 which are connected to the electrodes 2 and 3 and are adapted to be wound upon the drums 15 and 16.

The motor 10, which governs the operation of the electrode 3, is controlled by means of a regulator 20, in accordance with the current supplied to the electrode 3, and the motor 9, which operates the electrode 2, is governed by a regulator 21, in accordance with the current that is supplied to the furnace through the electrode 2. The regulator 20 embodies a main control electromagnet 22 having a winding 23, which is connected to the supply conductor 8 by means of a current transformer 24, an adjustable resistor 25 being connected across the winding 23 for regulating the speed of operation of the main control electromagnet 22. The main control electromagnet 22 further em-

- bodies a core member 26 which is pivotally connected to a contact arm 27 and is maintained in a retracted position by means of a spring 28. The contact arm 27 is provided 5 with a contact member 30 which is selectively moved into engagement with contact fingers 31 and 32, according to the energization of the main control electromagnet 22. An auxiliary polarized magnet 33, having a 10 winding 34 and a core 35, is connected to the contact arm 27 and is adapted to oppose the action of the main control magnet 22, under predetermined conditions, for preventing a hunting action by the regulator. The winding 15 34 of the auxiliary electromagnet is connected across the armature 12 of the motor 10 and is shunted by means of an adjustable resistor 36 for adjusting the speed of its operation.
- 20 Two electromagnetic switches 37 and 38, which are selectively operated by means of the main control magnet 22, are provided for determining the direction of rotation of the motor 10 and, consequently, the position 25 of the electrode 3 relative to the bath of material 5. The switch 38 embodies a winding 39, which is connected across an auxiliary supply circuit, comprising conductors 40 and 41, whenever the contact members 30 and 31 30 are in engagement with each other, and three switch members 42, 43 and 44. The two switch members 42 and 43 serve for connecting the armature 12 of the motor 10 through a resistor 45, across the supply conductors 40 and 41, in order to effect rotation 35 of the motor 10 in a counter-clockwise direction and thus raise the electrode 3. The switch 37 embodies a winding 46, which is connected across the supply conductors 40 and 41 when the contact terminals 40 40 and 32 are in engagement with each other, and three switch members 47, 48 and 49. The two switch members 47 and 48 serve for connecting the armature 12 of the motor 10 45 across the supply conductors 40 or 41 in a manner to effect rotation of the motor 10 in a clockwise direction and thus permit the lowering of the electrode 3. The switch members 49 and 44 of the switches 37 and 38 50 serve for completing a dynamic braking circuit through the armature 12 whenever the two switches are in released positions. The field winding 14 of the motor 10 is connected across the supply conductors 40 and 41, through an adjustable resistor 50.
- 55 The regulator 21, which governs the operation of the motor 9 in accordance with the current supplied to the electrode 2, embodies a main-control or contact-making ammeter 52 having an energizing winding 53 and a core member 54, which is pivotally connected to a contact arm 55. The core member 54 is retracted by means of a spring 56, and the energizing winding 53 is connected to the supply conductor 7 by means of a cur-
- rent transformer 57. An adjustable resistor 58 is provided for governing the sensitivity of the magnet. The contact arm 55 is provided with a contact terminal 60 which selectively engages the contact fingers 61 and 62 according to the energization of the magnet 52.
- An auxiliary polarized magnet 63, comprising a winding 64 and a core member 65, which is pivotally connected to the contact arm 55, is provided for opposing the action of the electromagnet 52 under predetermined conditions so as to prevent a hunting action by the regulator 21. The winding 64 is connected directly across the armature 11 of the motor 9 in order to be energized in accordance with the counter-electromotive force of the motor, and an adjustable resistor 66 is connected across the winding 64 for governing the sensitivity of the auxiliary magnet 63.
- Two switches 69 and 70 are selectively controlled by the main-control electromagnet 52 for governing the direction of rotation of the motor 9 and, accordingly, the position of 90 the electrode 2. The switch 70 embodies a winding 71, which is connected across the supply conductors 40 and 41 whenever the contact members 60 and 61 are in engagement with each other, and three contact 95 members 72, 73 and 74. The two contact members 72 and 73 serve to connect the armature 11 through a resistor 75 across the supply conductors 40 and 41 whenever the switch 70 is in an operative position. The 100 motor 9 is rotated in a counter-clockwise direction when connected to the supply conductors 40 and 41, through the switch members 72 and 73, in order to raise the electrode 2 from the bath of material 5.
- The switch 69 embodies a winding 76, which is connected across the supply conductors 40 and 41 when the contact members 60 and 62 are in engagement with each other, and three switch members 77, 78 and 79. 110 The two switch members 77 and 78 serve for connecting the armature 11 of the motor 9 across the supply conductors 40 and 41 in a manner to effect clockwise rotation of the motor and thus permit a lowering of the electrode 2. The switch members 79 and 74 of the switches 69 and 70 serve for completing a dynamic-braking circuit through the armature 11 whenever the switches are in a released position. The field winding 13 of 115 the motor 9 is connected across the supply conductors 40 and 41, through an adjustable resistor 80.
- In order to explain the operation of the furnace, the control of one motor and its associated electrode by one of the regulators will be set forth in detail. Assuming the electrode 3 to be in such position relative to the bath of material 5 that the current flowing through the conductor 8 is above normal 120

value, the energization of the winding 23 of the contact-making ammeter 22 will be increased in a manner to effect engagement between the contact members 31 and 30. Upon engagement of the contact members 30 and 31, the switch 38 is operated to complete a circuit from the supply conductors 40, 41 to effect rotation of the motor 10 in a counter-clockwise direction and thus effect a 10 raising of the electrode 3. The auxiliary electromagnet 33, which is connected across the armature 12 of the motor, is energized in accordance with the counter-electromotive force of the armature 12 and, as has been explained heretofore, opposes the action of the contact-making ammeter 22. Consequently, when the counter-electromotive force of the armature 12 is raised to a predetermined point, the auxiliary magnet 33 will overcome 20 the action of the contact-making ammeter 22 and de-energize the motor 10 by releasing the switch 38. In this regard, it may be noted that the time at which the auxiliary electromagnet 33 overcomes the action 25 of the magnet 22 may be adjusted by means of the resistors 25 and 36 which are respectively associated with the windings 23 and 34 of the two electromagnets. The auxiliary magnet is adapted to stop the motor 10 30 at such point as to prevent over travel thereby and consequent hunting by the regulator 20.

In case the electrode 3 is raised above the bath of material 5 to such position that a 35 current below normal value is flowing through the supply conductor 8, the energization of the contact-making ammeter 22 is reduced to such point that engagement is effected between the contact members 30 and 32. Upon engagement of the contact members 30 and 32, the switch 37 is operated for connecting the armature 12 of the motor 10 across the supply conductors 40 and 41. Thus the motor is operated in a clockwise 40 direction to permit the lowering of the electrode 3. Simultaneously with the operation of the motor 10, the polarized auxiliary magnet 33 is energized by the counter-electromotive force of the armature 12 to separate 45 the contact members 30 and 32.

It is deemed inadvisable to completely trace the operation of the regulator 21 for governing the motor 9 to determine the position of the electrode 2, inasmuch as the 50 regulator 21 operates in a manner similar to the operation above set forth in discussing the regulator 20. From the above description, it will be noted that the two electrodes 2 and 3 are governed in accordance 55 with the current which is supplied to them through the conductors 7 and 8 and that a hunting action is prevented by the auxiliary polarized magnets 33 and 63, which are governed in accordance with the counter- 60 electromotive force of the motors 9 and 10.

Modifications in the system and arrangement and location of parts may be made within the spirit and scope of my invention and such modifications are intended to be covered by the appended claims.

70

I claim as my invention:

1. In a regulator for an electric furnace having an operating motor, an electromagnetic device having two electromagnets for controlling the operation of the motor, one of said electromagnets being energized in accordance with the current supplied to the furnace and the second electromagnet being energized in accordance with the electrical conditions of the motor to prevent hunting 80 action by said device.

2. In combination, an electric furnace, a motor for adjusting an electrode of the furnace, a regulator comprising means for operating the motor in accordance with the current supplied to the furnace and for completing a dynamic braking circuit through the motor, and means controlled by the counter-electromotive force of the motor for preventing hunting action by the 90 regulator.

3. In combination, an electric furnace having an operating motor, and a regulator comprising a main electromagnet for operating the motor in accordance with the current supplied to the furnace and means comprising an auxiliary electromagnet governed in accordance with the motor electrical conditions for opposing the action of the main electromagnet to prevent hunting action by it.

4. The combination with a supply circuit, and an electric furnace connected to the supply circuit, of a motor for adjusting the furnace, an electromagnet operated in accordance with the current supplied to the furnace, two switches selectively operated by said electromagnet for governing the operation of the motor, and means controlled by the motor for preventing hunting action 105 by the electromagnet.

5. The combination with a supply circuit, an electric furnace connected to the supply circuit, and a motor for varying the arc obtained in the furnace, of an electromagnet operated in accordance with the current supplied to the furnace and two switches controlled by said magnet for governing the operation of said motor, and means controlled by the motor for preventing 110 hunting action by said electromagnet.

6. The combination with a supply circuit and an electric furnace connected to the supply circuit, of a motor for raising and lowering a furnace electrode, an electric regulator comprising a main electromagnet for selectively effecting rotation of the motor in accordance with the current supplied to the furnace, and means comprising an auxiliary magnet controlled by said motor 125 130

for modifying the action of the main magnet to prevent hunting action by the regulator.

7. The combination with a supply circuit, 5 and an electric furnace connected to the supply circuit, of a motor for adjusting the arc obtained in the furnace, a regulator for selectively operating the motor in accordance with the current supplied to the furnace 10 and auxiliary means comprising a magnet controlled by the counter-electromotive force of the motor for modifying the action of said regulator to prevent hunting action.

8. The combination with a polyphase supply 15 circuit, and an electric furnace connected to the supply circuit, of motors for operating the furnace electrodes, and regulators for severally operating said motors in accordance with the current supplied to the 20 furnace, and means controlled by the counter-electromotive force of the motors for modifying the action of said regulators to prevent hunting action.

9. The combination with an electric furnace 25 having a plurality of electrodes, and a polyphase supply circuit connected to the furnace, of motors for varying the position of the electrodes, regulator means for selectively operating the motors in a forward and 30 in a reverse direction according to the current supplied to the furnace and for completing dynamic braking circuits through the motor, and means governed by the counter-electromotive force of the motors 35 for preventing hunting action by the regulator means.

10. In a regulator for an electric furnace having an electric motor for adjusting the 40 arc formed therein, an electromagnet operated in accordance with the current supplied to the furnace, two switches controlled by said electromagnet for operating the motor in a forward and in a reverse direction and for completing a dynamic-braking circuit 45 through the motor under certain conditions, and means controlled by the motor for preventing hunting action by said electromagnet.

11. In a regulator for an electric furnace 50 having an electric motor for adjusting the arc formed therein, electromagnetic means operated in accordance with the current supplied to the furnace, two switches selectively operated by said means for effecting operation of the motor either in a forward or in a reverse direction, an electromagnet for opposing the action of said electromagnetic means, and means for energizing said electromagnet in accordance with the counter-electromagnetic force of the motor to prevent hunting action by the electromagnetic means.

12. In a regulator for an electric furnace, 60 the combination comprising an electric motor and a main control element for govern-

ing the operation of said motor, said element comprising a coil energized in accordance with the value of the current supplied to the furnace and a coil energized in accordance with the operation of the motor.

13. In combination, a plurality of movable electrodes, a motor for raising and lowering each of said electrodes, a regulator for governing each motor in accordance with the value of current supplied to the associated electrode and for completing a dynamic braking circuit through the motor, and means for modifying the operation of the regulator in accordance with the electric conditions of the associated motor to prevent hunting action.

14. In combination, a plurality of energy-translating devices, means for severally adjusting said devices in accordance with the amount of current being supplied thereto, 85 and means controlled by an electrical condition of said adjusting means for changing the action of said adjusting means to prevent hunting action.

15. The combination with a supply circuit 90 and a plurality of energy-translating devices connected thereto, of regulators comprising means for severally adjusting said devices in accordance with the current traversing said devices and means controlled by 95 an electrical condition of said adjusting means for changing the action of said adjusting means to prevent hunting action.

16. The combination with a supply circuit 100 and a plurality of energy-translating devices connected thereto, of means for adjusting said devices, regulating means for controlling said adjusting means in accordance with the amount of current being supplied to said devices and means controlled 105 by an electrical condition of said adjusting means for changing the action of said regulating means to anticipate and prevent hunting.

17. In combination, a supply circuit, a 110 plurality of energy-translating devices connected thereto, means for severally adjusting said devices to maintain a predetermined value of current translated, regulating means for said adjusting means, and 115 means effective during the operation of said adjusting means for changing the action of said regulating means in proportion to the variation from said predetermined value.

18. In combination, a supply circuit, a 120 plurality of energy-translating devices connected thereto, means for severally adjusting said devices to maintain a predetermined value of current translated, regulating means for said adjusting means, and means 125 for causing said regulating means to de-energize said adjusting means before said predetermined value of energy is reached, the difference between the value at which said adjusting means is de-energized and said 130

predetermined value being in accordance with an electrical condition of said adjusting means.

19. The combination, an electric furnace a motor for adjusting an electrode of the furnace, a regulator comprising means for operating the motor to maintain a predetermined value of current through said furnace, and means for causing said regulator to de-energize said motor before said predetermined value is reached, the difference in value at which said motor is de-energized and said predetermined value being proportional to the counter electromotive force of said motor.

20. The combination with a supply circuit and an electric furnace connected thereto, of a motor for raising and lowering a furnace electrode, an electric regulator comprising a main electromagnet for selectively effecting rotation of the motor to maintain a predetermined value of current traversing said electrode and means comprising an auxiliary magnet controlled by said motor

25 for so modifying the action of the main magnet as to cause it to effect de-energization of said motor before said predetermined value of current through said electrode is reached.

30 21. The combination with a supply circuit and an electric furnace connected thereto, of a motor for raising and lowering a furnace electrode, an electric regulator comprising a main electromagnet for selectively effecting rotation of the motor to maintain

a predetermined value of current traversing said electrode, and means comprising an auxiliary magnet controlled by said motor for so modifying the action of the main magnet as to cause it to effect de-energization of said motor before said predetermined value of current through said electrode is reached, the difference between the current value at which said motor is de-energized and said predetermined current value being directly in proportion to an electrical condition of said motor.

22. The combination with a supply circuit and an electric furnace connected thereto, of a motor for raising and lowering a furnace electrode, an electric regulator comprising a main electromagnet for selectively effecting rotation of the motor to maintain a predetermined value of current traversing said electrode, and means comprising an auxiliary magnet controlled by said motor for so modifying the action of the main magnet as to cause it to effect de-energization of said motor before said predetermined value of current through said electrode is reached, the difference between the current value at which said motor is de-energized and said predetermined current value being directly in proportion to the counter electromotive force of said motor.

In testimony whereof, I have hereunto subscribed my name this 18th day of Oct. 1918.

ROBERT D. EVANS.
